UNITED STATES PATENT OFFICE.

PETER ADAMS, OF BUFFALO, NEW YORK, ASSIGNOR TO CHARLES G. SHEPARD AND WALTER J. SHEPARD, BOTH OF SAME PLACE.

DESIGN FOR A TOY PISTOL.

SPECIFICATION forming part of Design No. 17,397, dated June 21, 1887.

Application filed April 11, 1887. Serial No. 234,431. Term of patent 7 years.

To all whom it may concern:

Be it known that I, PETER ADAMS, of the city of Buffalo, in the county of Erie and State of New York, have invented and produced a new and original Design for Toy Pistols, of which the following is a specification.

My invention relates to toy pistols, and has for its object to render the same attractive in appearance by an ornamentation applied to the barrel in front of the hammer.

In the accompanying drawings, Figures 1 and 2 represent two slightly different applications of my design.

Like letters of reference refer to like parts in both figures.

A represents the barrel of the pistol, B the handle, C the hammer, and D the cup. The latter is surrounded by an enlargement, E, re-

presenting the head of a living creature with its mouth wide open, the cup D being arranged in the mouth.

In Fig. 1 the enlargement E has the form of the head of a negro, while in Fig. 2 it represents the head of a lion.

I claim as my invention—

The design for a toy pistol, consisting of a handle, B, hammer C, barrel A, and an enlargement, E, arranged on the barrel in front of the hammer and representing the head of a living creature, substantially as set forth.

Witness my hand this 5th day of April, 1887.

PETER ADAMS.

Witnesses:

CARL F. GEYER,
JNO. J. BONNER.
